UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SWITCH MECHANISM.

1,399,499.

Specification of Letters Patent.

Patented Dec. 6, 1921.

Application filed September 6, 1918. Serial No. 252,877.

To all whom it may concern:

Be it known that I, HUBERT F. KRANTZ, residing at Brooklyn, in the county of Kings and State of New York, have invented certain new and useful Improvements in a Switch Mechanism, of which the following is a specification.

This invention relates to a switch mechanism.

10 The object of the invention is to provide a switch mechanism in which the main line conductors may be connected at either side of the mechanism.

15 A further object is to provide a switch mechanism of the above character in which the live parts are suitably protected within a casing fitted with an entrance door which may not be opened when the switch is "on".

20 A further object is to provide means whereby a switch mechanism of the kind indicated may not be moved "on" while the door of the casing is open.

25 A further object is to provide a switch mechanism of the kind indicated including a barrier disposed within the casing to stand between the door opening and the live contacts so as to protect an operator from coming into engagement with said live contacts when the door is open, the barrier being adapted to provide a separate fuse compartment accessible through the door opening.

30 A further object is to provide a new and improved switch operating mechanism associated with a new and improved form of door interlock.

35 A further object is to provide improved means for effecting a quick break movement of the switch blades.

40 A more detailed object is to provide a switch mechanism associated with a fuse and fuse clips, and including movable switch blades connected at least one with each of the opposite fuse clips, the switch blades being movable for engaging suitable contacts to close a circuit through the fuse.

45 Other objects and aims of the invention, more or less specific than those referred to above, will be in part obvious and in part 50 pointed out in the course of the following description of the elements, combinations, arrangements of parts and applications of principles, constituting the invention; and

the scope of protection contemplated will be indicated in the appended claims.

55 In the accompanying drawings which are to be taken as a part of this specification, and in which I have shown merely a preferred form of embodiment of the invention:

60 Figure 1 is a transverse sectional view taken through a switch mechanism constructed in accordance with this invention.

Fig. 2 is a longitudinal sectional view taken substantially upon the plane of line 65 II of Fig. 1.

Fig. 3 is a horizontal sectional view taken substantially upon the plane line III of Fig. 1, a part of the barrier being broken away to better disclose the arrangement of parts 70 therebeneath, and

Fig. 4 is a diagrammatic view illustrating different positions of the switch mechanism and associated parts.

75 Referring to the drawings for describing in detail the exemplary structure shown therein, the reference character L indicates the casing. This may be made up in any suitable manner or of any appropriate material. Preferably, however, it is constructed of sheet metal parts suitably shaped and connected together as indicated so as to provide a bottom wall 1, side walls 2 and end walls 3. The top wall, as 4, is provided with a door 5 pivotally connected, as at 6, 80 to swing into open and closed positions. A flange, as 7, is arranged at the free edge of the door for overlapping the adjacent side wall 2 and a suitable stop 8 is provided for limiting the opening movement.

85 Within the casing is a base plate G. This base plate is fixed to the bottom wall 1 and carries two sets of stationary contacts, as 9 and 10, upon its upper face. The contacts of each set are arranged in a row. The two rows are spaced apart and a partition 11 is interposed therebetween. The partition is preferably fixed to the base plate and both are of suitable insulating material.

90 Each of the contacts 9—10 are of L-shape. One leg is fixed flat against the surface of the base plate G while the other leg projects upwardly from the base plate to provide a more or less resilient contact surface, 105 as 12, against which the lower beveled ends,

as 13, of the switch blades H are adapted to engage.

Conductor terminal pieces, as 14 and 15, are connected with the contacts 9 and 10 respectively for the attachment of main and branch line conductors.

Of course it will be understood that any required number of contacts and switch blades may be provided at each side of the 10 partition 11 according to whether the switch mechanism is to be used for one, two or three wires. In the instance illustrated, three wires are to be employed and hence there are three contacts and switch blades at each 15 side of the barrier.

The switch blades are supported in carriers of the same general type as is fully shown and described in my Patent 1,248,415, November 22, 1917, and in my pending application Serial No. 175,192. These carriers each include a pair of clamp plates 16 between which the blades are held, suitable insulating blocks, as 17, being interposed to insulate the blades from the plates and from 25 each other. At the opposite ends of the carriers suitable connecting members, as 18, are provided, said connecting members being formed with pivot extensions 19 which extend through a pair of supporting brackets 30 projecting upwardly from the ends of the base plate G. The extensions 19 are slotted, as at 21, to receive the ends of coil springs 22 which surround the extensions and have their opposite ends arranged to engage stop pins 23 so that the springs constantly urge the carriers and blades into the 35 "off" position.

In order to operate the switch blades into the "on" position, a toggle is provided consisting of two links, as 24 and 25. These links are connected together by a pivot 26 and the outer end of the link 24 is pivotally connected, as at 27, to an upwardly extending arm 28 formed upon one of the switch 45 blade carriers, while the link 25 has its outer end pivotally connected, as at 29, to an upwardly extending arm 30 formed upon the other switch blade carrier. When the switch blades are in the "off" position, the toggle is forced into broken position the switch blades are thereby forced "on" against the contacts 9 and 10.

An operating handle 31 is provided exteriorly of the casing for operating the toggle. This is connected with a push rod 32 which extends into the casing and which is slidably mounted to move back and forth in a plane between the carriers. A suitable guide bearing, as 33, is formed through the top wall of the casing, while a second guide bearing 34 is formed through a flange 35 provided upon the adjacent supporting bracket 20.

The slide rod 32 is longitudinally slotted, 65 as at 36, to receive the pivot pin 26 of the

toggle, and the lower end of the rod is formed with a shoulder, as 37, for engaging beneath the under surface of the flange 35 to limit the upward movement of the rod.

The upper end wall, as 38, of the slot 36, 70 is disposed in a position relative to the shoulder 37 such that it limits breaking movement of the toggle in a position with the switch blades spaced an appropriate distance from the contact surfaces 12. 75

The lower end wall, as 39, of the slot 36, is in such relation to the shoulder 37 that, when the toggle stands made, an upward movement of the slide rod sufficient to bring the shoulder 37 against the flange 35, will 80 just raise the surface 39 sufficient to lift the pivot 26 above a straight line between the pivots 27 and 29 to thereby enable the springs 22 to snap the toggle to its full "off" position. 85

The blades H may be of any suitable material, but are preferably laminated and are flexible so that they bend somewhat when in engagement with the contact surfaces 12. The surfaces 12 are also bent back slightly 90 by the same force and all of this bending as clearly illustrated in Fig. 4, produces a force which is suddenly released and which augments the force of the springs 22 in producing an extremely quick-break movement of 95 the surfaces 13 away from the surfaces 12 when the toggle is broken. As the toggle passes its center position, the surfaces 12 follow the surfaces 13 a slight distance giving impetus to said surfaces 13 and maintaining engagement therewith until the surfaces 12 reach their normal positions, or until a certain velocity of movement is attained by the surfaces 13. The bending of the blades meanwhile also is being relieved so 105 that at the moment of breaking contact a considerable degree of momentum has already been set up in the blades and the break will be extremely sudden.

The supporting brackets 20 are also utilized for supporting the barrier, as A. This barrier consists of a plate or wall of suitable insulating material, and is disposed as a partition dividing the interior of the casing into an upper and lower compartment. The 110 upper compartment is adapted to contain the fuses, as 40, in a position of ready accessibility when the door 5 is open, while the lower compartment is shielded by the barrier and is adapted to contain the switch 115 blades and the contacts 9 and 10 so that these live parts, especially the main line contacts, may not be readily accessible when the door is open. The fuses 40 are spaced apart side by side along the length of the barrier A, 120 and each is preferably supported in a pair of clips 41. One of these clips is connected with one of the switch blades H by a suitable flexible connection, as 42, while the other clip is similarly connected with the op- 125 130

posite switch blade H by a suitable flexible connection, as 43.

Similar connections are provided between each fuse, and its respective pair of switch blades.

Each fuse is thus disposed between a pair of switch blades and it is, therefore, immaterial which of said switch blades is associated with the main line contact. The main line conductors may, therefore, be connected with either of said sets of contacts 9 or 10 with equal correctness. There is thus no likelihood of a careless operator connecting the main line conductors with the wrong terminal pieces as has often happened in connection with switches which have heretofore been used.

The interlock between the switch operating mechanism and the door includes a bracket 44 which is fixed to the inner surface of the door and which carries a pin 45 disposed to engage within an arcuate slot 46 formed in the link 25 of the toggle. The slot 46 is made so that when the toggle is in its broken position the slot is concentric with the pivot or hinge 6 of the door to thus permit the pin 45 to travel freely along the slot as the door is opened or closed. Whenever the toggle is moved out of its broken position, however, the position of the slot is, of course, so altered as to prevent movement of the pin 45 along the slot and to thereby retain the door closed. The inner end of the slot is slightly enlarged, as at 47, so as to permit unobstructed movement of the link 25 when the door is closed. This enlargement provides a surface or shoulder 48 in such position that when the toggle is made, as shown in Fig. 4, said shoulder 40 stands directly in the path of movement of the pin 45 and thus constitutes a positive barrier to any opening movement of the door so long as the switch remains "on".

Further, when the switch is "off" and the door is open, as also shown in Fig. 4, the slot provides a surface, as 49, which engages the pin 45 to positively prevent the making of the toggle until the door has been closed and the pin 45 removed from the surface 49 to the lower end portion of the slot. It is noted, in this connection, that the surface 49 stands in such relation to the pivots 6 and 29 that any pressure from the operating handle tending to swing the toggle link 25 down toward the dotted line position in Fig. 4, will result in a direct and positive push of the pin 45 away from the pivot 6 without imparting any tendency to close the door.

The operation of the device is believed to be entirely clear from the above description. Downward pressure upon the operating handle 31 moves the toggle into made position with both of the blades pressing against the respective contacts 9 and 10, as clearly shown by the dotted lines in Fig. 4. The

movement of the toggle into made position may be limited by any suitable means, but is preferably limited by engagement with the upper surface of the flange 35 of the support 20. In this position the pivot 26 is slightly below the plane of a straight line extending between the pivots 27 and 29 so that the toggle will remain made, or locked, and the operating handle will remain down as long as desired. To break the toggle the operating handle is simply withdrawn so that the end wall 39 of the slot 36 engages the pivot 26 and moves the pivot 26 above center so that the springs 22, augmented by the power of the switch blades and the contacts as above referred to, will snap the toggle fully "off".

The barrier A is preferably connected to the flanges 35 of the supporting brackets 20 by means of suitable screws or bolts 51 which may be removed with a proper instrument. These screws may engage threaded apertures, as 52, formed in the flanges. By this means the barrier, while normally held stationary in position above and guarding the live contacts, may yet be removed when occasion requires to afford access to all of the parts therebeneath.

While it is above stated that the resiliency of the contacts 9 and 10, as well as the resiliency of the blades H, serve to supplement the springs 22 in producing a quick break movement of the mechanism, nevertheless, it is apparent that the resiliency of the contacts alone might serve in some instances to produce quick break movement of the switch blades. This is also equally true with regard to the resilient character of the switch blades. Where both the switch blades and contacts are resilient, a sufficiently quick break is afforded so that in many instances the springs 22 may be entirely dispensed with or reduced in size. The springs 22 may even, in some instances, be looked upon as being only for the purpose of maintaining the switch blades in their full "off" position when the toggle is broken.

As many changes could be made in this construction without departing from the scope of the invention as defined in the following claims, it is intended that all matter contained in the above description or shown in the accompanying drawings, shall be interpreted as illustrative only and not in a limiting sense.

Having thus described my invention, what I claim as new and desire to secure by Letters Patent is:—

1. A switch mechanism comprising a pair of independently mounted relatively movable switch blades, contacts one for each of said switch blades, a fuse connected in series between said switch blades, and means for operating the switch blades relatively with

respect to the fuse and into and out of engagement with said contacts respectively.

2. A switch mechanism comprising a pair of elements spaced apart and adapted for receiving the opposite ends of a fuse, a pair of contacts one associated with each of said elements, and switch devices relatively movable with respect to the fuse and to one another for making and breaking electrical connection between each of said elements and its respective contact.

3. A switch mechanism comprising a pair of elements spaced apart and adapted to receive a fuse between them, a pair of contacts one associated with each of said elements, a pair of switch blades one electrically connected with each of said elements and being movable relatively to each other into and out of engagement with said contacts respectively, and means for so moving said switch blades.

4. A switch mechanism comprising a pair of elements spaced apart and adapted to receive a stationary fuse between them, a pair of contacts one associated with each of said elements, a pair of switch blades one flexibly and conductively connected with each of said elements and having contact portions disposed to move toward each other and into engagement with said mentioned contacts, and means for so moving said switch blades.

5. A switch mechanism comprising a pair of elements spaced apart and adapted to receive a stationary fuse between them, a pair of contacts one associated with each of said elements, a pair of switch blades one flexibly and conductively connected with each of said elements, means whereby said switch blades are independently pivotally supported to swing into and out of engagement with said contacts respectively, and means for so swinging said switch blades.

6. A switch mechanism comprising a pair of elements spaced apart and adapted to receive a fuse between them, a pair of contacts one associated with each of said elements, a pair of switch blades one electrically connected with each of said elements, means whereby said switch blades are independently pivotally supported to swing into and out of engagement with said contacts respectively, a toggle connected between said switch blades movable into made and broken positions for swinging the switch blades, and means for operating the toggle.

7. A switch mechanism comprising a pair of elements spaced apart and adapted to receive a fuse between them, a pair of contacts one associated with each of said elements, a pair of switch blades one electrically connected with each of said elements, means whereby said switch blades are independently pivotally supported to swing into

and out of engagement with said contacts respectively, and means for swinging said switch blades, said means being of a character to lock the switch blades in engagement with said contacts.

70

8. A switch mechanism comprising a pair of elements spaced apart and adapted to receive a fuse between them, a pair of contacts one associated with each of said elements, a pair of switch blades one electrically connected with each of said elements, means whereby said switch blades are independently pivotally supported to swing into and out of engagement with said contacts respectively, means for swinging said switch blades, said means including a toggle movable into made and broken positions and adapted when in made position to hold the switch blades locked in engagement with said contacts, and means for operating the toggle.

75

9. A switch mechanism comprising a pair of independently mounted switch blades, a pair of contacts one for each of said switch blades, connections between the switch blades operable to move the switch blades into and out of engagement with said contacts respectively, a single operating handle for operating said connections, and a stationary fuse electrically connected in series between said switch blades.

80

10. A switch mechanism comprising a casing, a barrier within the casing dividing the casing into two compartments, a pair of contacts arranged within one of said compartments, a pair of switch blades also arranged in the same compartment operable into and out of engagement with said contacts, means to operate the switch blades, and a pair of fuse clips arranged within the other compartment being electrically connected one with each of said switch blades.

85

11. A switch mechanism comprising a casing, a barrier within the casing dividing the casing into two compartments, a pair of contacts arranged within one of said compartments spaced apart, a pair of switch blades arranged in the same compartment spaced a relatively greater distance apart and having portions movable toward each other into engagement with said contacts respectively, means for so moving said switch blades, and a pair of fuse clips supported by said barrier within the other compartment and electrically connected one with each of the switch blades.

90

12. A switch mechanism comprising a casing, a barrier within the casing dividing the casing into two compartments, a pair of contacts arranged within one of said compartments, supports for said barrier spaced apart, a pair of switch blades also within the same compartment operable into and out of engagement with said contacts respectively, carriers for said switch blades, said

95

100

105

110

115

120

125

130

- carriers being independently pivotally supported by said mentioned supports, means for swinging the carriers to operate the switch blades, fuse clips carried by said barrier in the other compartment, and flexible connections extending between said fuse clips and said switch blades respectively.
13. A switch mechanism comprising a pair of switch blades, pivotal supports for the switch blades whereby said switch blades are independently mounted, a pair of contacts with which the switch blades are adapted to coöperate, a toggle extending between and being connected with the switch blades to swing the switch blades in unison, and a push rod connected with the knee joint of the toggle for operating the toggle.
14. A switch mechanism comprising a pair of switch blades, pivotal supports for the switch blades whereby said switch blades are independently mounted, a pair of contacts with which the switch blades are adapted to coöperate, a toggle extending between and being connected with the switch blades adapted to move into made and broken positions for swinging the switch blades, means normally urging the toggle to broken position and at the same time urging the switch blades "off", and means for operating the toggle, said means having lost motion connection with the toggle whereby to permit full breaking movement of the toggle following the initial breaking movement.
15. A switch mechanism comprising a pair of switch blades, pivotal supports for the switch blades whereby said switch blades are independently mounted, a pair of contacts with which the switch blades are adapted to coöperate, means extending between and being connected with the switch blades operable to swing the switch blades in unison, and an operating handle for the said means permitting independent movement thereof with respect to the handle.
16. A switch mechanism comprising a pair of switch blades, pivotal supports for the switch blades whereby said switch blades are independently mounted, a pair of contacts with which the switch blades are adapted to coöperate, means extending between and being connected with the switch blades operable to swing the switch blades in unison, said means being of a character to permit quick break movement of the switch blades, and said contacts being resilient and being adapted to be depressed when engaged by said switch blades to thereby produce a quick break movement of the switch blades away from said contacts.
17. A switch mechanism comprising a pair of switch blades, pivotal supports for the switch blades whereby said switch blades are independently mounted, a pair of contacts with which the switch blades are adapted to coöperate, means extending between and being connected with the switch blades operable to swing the switch blades in unison, said means being of a character to permit quick break movement of the switch blades, and both said contacts and said switch blades being resilient and being adapted to stand bent while in "on" position so as thereby to store an energy operable to produce a quick break movement of the switch blades when said switch blades are moved "off".
18. A switch mechanism comprising a pair of switch blades, pivotal supports for the switch blades whereby said switch blades are independently mounted, a pair of contacts with which the switch blades are adapted to coöperate, means extending between and being connected with the switch blades operable to swing the switch blades in unison, said means being of a character to permit quick break movement of the switch blades, means connected with each of said switch blades constantly urging the switch blades "off", and both said contacts and said switch blades being resilient and being adapted to stand bent while in "on" position so as thereby to store an energy adapted to quicken the breaking movement of the switch blades.
19. A switch mechanism comprising a casing having an entrance door thereto, switch blades arranged within the casing, movable into "on" and "off" positions, a toggle for operating the switch blades, one link of the toggle having a slot formed therein, and means movable with the door disposed to traverse said slot coöperative to prevent opening of the door while the switch blades are "on" and to prevent "on" movement of the switch blades while the door is open.
20. A switch mechanism comprising a casing having an entrance door thereto, a switch blade arranged within the casing, movable into "on" and "off" positions, a toggle for operating the switch blade, and means fixed rigidly to move with the door disposed for directly engaging the toggle to coöperate therewith for preventing opening of the door while the switch blade is "on" and for preventing "on" movement of the switch blade while the door is open.
21. A switch mechanism comprising a casing having an entrance door thereto, a pair of switch blades arranged within the casing movable into "on" and "off" positions, a toggle extending between and being connected with the switch blades for operating said switch blades in unison, and means carried by the door coöperative with the toggle to prevent opening of the door while the switch blades are "on" and to prevent "on" movement of the switch blades while the door is open.
22. A switch mechanism comprising a cas-

ing having an entrance door thereto, a pair of switch blades arranged within the casing movable into "on" and "off" positions, a toggle extending between and being connected with the switch blades for operating said switch blades in unison, said toggle including a part having a slot formed therein, and a part movable with the door disposed to traverse said slot and being adapted thereby to prevent opening of the door when the switch blades are "on" and to prevent "on" movement of the switch blades while the door is open.

23. A switch mechanism comprising a casing having an entrance door thereto, a pair of switch blades arranged within the casing movable into "on" and "off" positions, a toggle extending between and being connected with the switch blades for operating said switch blades in unison, the door being pivotally mounted to swing into open and closed positions, the toggle providing a part having an arcuate slot formed therein disposed when the switch blades are "off" to stand substantially concentric with the door pivot, and a part carried by the door for traversing said slot whereby to permit unobstructed opening of the door when the switch blades are "off" and to prevent "on" movement of the switch blades while the door is open.

24. A switch mechanism comprising a casing having a pivotally mounted entrance door thereto, a switch blade within the cas-

ing movable into "on" and "off" positions, 35 means for operating the switch blade including a toggle, the toggle including a part having an arcuate slot formed therein disposed when the switch blade is "off" to stand substantially concentric with the door pivot, and a part carried by the door for traversing said slot whereby to permit unobstructed opening of the door when the switch blade is "off" and to prevent "on" movement of the switch blade when the door 40 is open.

25. A switch mechanism comprising a casing having a pivotally mounted entrance door thereto, a switch blade within the casing movable into "on" and "off" positions, 45 means for operating the switch blade including a toggle, one link of the toggle having an arcuate slot therein disposed when the switch blade is "off" to stand substantially concentric with the door pivot, a part 50 carried by the door for traversing the slot when the switch blade is "off", and the slot having a shoulder formed therein disposed when the switch blade is "on" to stand in the path of movement of said part carried 55 by the door to thereby prevent opening of the door while the switch blade is "on".

In testimony whereof I affix my signature in the presence of two witnesses.
